UNITED STATES PATENT OFFICE.

EDWIN A. COX, OF SYRACUSE, NEW YORK, ASSIGNOR TO THE ROTOSPEED COMPANY,
OF DAYTON, OHIO, A CORPORATION OF OHIO.

STENCIL-PRINTING MACHINE.

1,070,419.

Specification of Letters Patent. Patented Aug. 19, 1913.

Application filed January 11, 1909. Serial No. 471,704.

To all whom it may concern:

Be it known that I, EDWIN A. COX, of Syracuse, in the county of Onondaga, in the State of New York, have invented new and useful Improvements in Stencil-Printing Machines, of which the following, taken in connection with the accompanying drawings, is a full, clear, and exact description.

This invention relates to certain improvements in stencil printing machines of the rotary type in which the waxed paper stencil together with the ink distributing pad are mounted upon a suitable drum or cylindrical segment adapted to be rotated by hand or other power in coaction with a suitable impression roller for feeding and printing sheets of paper successively one by one as they are fed thereto.

The primary object of my present invention is to simplify the paper feed and printing mechanisms and at the same time to render its action more positive and continuous whereby any skilled or unskilled operator may readily produce neat and accurately printed copies with greater rapidity than has heretofore been possible with this class of machines.

One of the specific objects is to provide a simple and comparatively inexpensive retarding means for preventing the simultaneous feeding by hand of more than one sheet at a time to the printing mechanism.

Another specific object is to provide a rotary abutment and suitable controlling mechanism actuated by and synchronized with the movement of the stencil supporting cylinder for properly registering the advance end of each sheet with the printing portion of the stencil and at the same time to provide for the adjustment of such actuating mechanism whereby the printing may be spaced varying distances from the advance end of the sheet.

Another object is to provide a simple means for attaching, tightening and releasing the perforated stencil supporting plate whereby it may be easily removed for cleansing or repairs and readily replaced in operative position.

A still further object is to provide the drum with an ink reservoir and suitable feed-

ing means whereby the ink may be expressed or ejected in such quantities as may be desired through the perforations of the stencil supporting plate and against the inking pad thereby rendering the operation of inking the pad more cleanly and less laborious.

Other objects and uses relating to special features of construction will be brought out in the following description.

In the drawings—Figures 1 and 2 are respectively a top plan and a side elevation of a stencil printing machine embodying the various features of my invention. Figs. 3 and 4 are respectively a transverse vertical sectional view and a longitudinal sectional view taken on lines 3—3, Fig. 1 and 4—4, Fig. 2, Fig. 3 being somewhat enlarged. Fig. 5 is an enlarged top plan of the stop roll and superposed presser plate showing adjacent portions of the frame and paper support. Figs. 6, 7 and 8 are enlarged detail end views of the stop roll and its controlling mechanism including portions of the stencil supporting cylinder and impression roll, the stop roll and its controlling mechanism being shown in different positions assumed as the paper progresses to or between the printing couple. Fig. 9 is an enlarged detail sectional view through a portion of the stencil supporting drum showing particularly the means for attaching the stencil and adjacent portion of the ink reservoir and piston plate for expelling the ink from the reservoir. Fig. 10 is a longitudinal sectional view partly broken away through one end of the ink reservoir showing the mechanism for operating the piston plate. Fig. 11 is a plan view partly broken away of the perforated stencil supporting plate. Figs. 12, 13 and 14 are sectional views taken respectively on lines 12—12, 13—13, and 14—14, Fig. 11, Fig. 14 showing the movable means for clamping the perforated plate to the drum. Fig. 15 is a sectional view taken on line 15—15 Fig. 4, showing an inner face view of one of the end guides for impression roller. Fig. 16 is an end view of a modified form of actuating mechanism for the stop rollers consisting of an adjustable toothed rack or ring on one end of the drum and adapted to engage a

100

mutilated gear on one end of the stop roller. Fig. 17 is an end view of a stop roller and presser plate used in connection with the actuating mechanism shown in Fig. 16. 5 Figs. 18 and 19 are sectional views taken respectively on lines 18-18 and 19-19, Fig. 16. Fig. 20 is a detail sectional view showing the ends of the presser roller and stop roller, together with a paper stripping device for stripping the sheet from the stencil as it is fed through the machine. Fig. 21 is an end elevation of a portion of the drum showing particularly the brake mechanism for preventing the rotation of the drum 10 backwardly.

15 This stencil printing machine comprises essentially a stop feed for registering and feeding the sheets to the printing couple, means for controlling the action of the stop 20 feed mechanism, and a supporting and retarding rest for the sheet to be printed whereby they may be readily fed by hand one at a time to the stop feeding device.

25 *Printing couple.*—The printing couple consists essentially of a stencil supporting drum —1— and an impression roll —2— mounted one above the other in a suitable supporting frame —3— and having their axes disposed in the same vertical plane and 30 parallel with each other. The stencil supporting drum —1— is actuated by intermeshing gears —4— and a suitable hand piece —5— and preferably consists of opposite end heads —6—, and a perforated stencil 35 supporting segment —7—. This stencil supporting segment —7— preferably consists of a perforated sheet metal plate of equal or greater area than that of ordinary legal cap or letter note paper and is substantially semi-cylindrical in form and is removably secured to the peripheries of the end heads —6— in a manner presently described, said segment together with the end heads forming a hollow drum with a clear 40 open space in one side to permit access to the interior of the drum for cleansing or applying ink from the interior through the perforations to the pad. The opposite ends of the perforated segment —7— are bent inwardly upon the main body and returned 45 outwardly forming lengthwise grooves —10— for receiving the ends of a stencil —9— and an ink pad —8— together with suitable fastening means as clamping bars 50 —11— and —11'— by which the ends of the stencil and pad are firmly retained in place wholly within the outer surface of the stencil.

55 The stencil supporting plate or segment —7— is provided with opposite end and intermediate pairs of slots —12— and —13—, the end slots being key-hole shape to receive corresponding pairs of studs —15— and —16— projecting from the peripheries of 60 the end heads —6— while the apertures

—13— are adapted to receive suitable studs —17— also projecting from the peripheries of the heads —6—. The studs —15— are in this instance permanently secured to inwardly projecting flanges on the end heads —6— and are provided at their outer ends with suitable heads which are spaced apart from the periphery of the heads a distance corresponding to the thickness of the stencil supporting plate or segment —7— and are of greater diameter than the smaller portions of the slots through which they pass so as to firmly lock the corresponding end of the segment to the drum heads against radial or lengthwise displacement. In like manner 70 the intermediate studs —17— are secured to the end heads —6— and project into the apertures —13— to retain the central portion of the plate against lateral movement, the apertures —13— being elongated in the 75 direction of length of the plate to permit said plate to be moved lengthwise in placing it upon or removing it from the end head —6—.

80 The studs —16— are movable longitudinally of the plate and are headed similar to the studs —15— but in this instance are mounted upon the outer ends of swinging arms —18— which extend radially of the drum and are pivotally mounted at their 85 inner ends upon the hubs of the end heads —6— thereby allowing adjustment of the studs —16— lengthwise of and in the same plane as the segment —7— to draw said segment tightly upon the drum heads and hold 90 it in its adjusted position. Any suitable means may be employed for moving these studs —16— lengthwise of the plate or segment which they are adapted to clamp in place and for this purpose I have shown an 95 operating bar —20— eccentrically mounted upon a pair of swinging members or levers —21— which are pivoted to the end heads —6— so that by moving the levers —21— in one direction the bar —20— will be forced 100 against the adjacent end of the arms —18— thereby moving the studs —16— against the outer ends of their slots and firmly drawing the ends of the stencil supporting plate 105 against the periphery of its supporting drums while on the other hand by shifting the lever in the other direction and thereby throwing the eccentric rod —20— away from the arms —18—, the studs —16— may be moved into registration with the other ends 110 of their respective openings thus permitting the stencil plate to be moved endwise in the same direction and removed from their clamping studs —15— and —17—. It is 115 evident, however, that many other forms of tightening and releasing devices may be employed to enable the stencil supporting plate to be easily and quickly clamped in place or removed for cleaning or repairs. Another 120 object in making the stencil plate removable 125

70

100

105

110

115

120

125

130

is to enable such plate with the stencil thereon to be removed and laid aside and another plate with a different stencil thereon substituted without removing either stencil from its supporting plate.

The stencil supporting drum is also provided with an ink reservoir —22— covering the inner face of the perforated portion of the segment —7— and located between opposite ends of said segment, which latter forms the outer wall of the reservoir, the inner wall of said reservoir consisting of a sheet metal plate —23— having its ends rigidly secured to the opposite ends of the segment and its intermediate portion spaced some distance apart from said segment forming a crescent shaped reservoir embracing the entire perforated portion of the segment. The inner wall of the reservoir is provided with an inlet —24— through which such reservoir may be filled, the inlet being normally closed by a suitable cap —25—. Within the reservoir and substantially coextensive therewith is a movable piston consisting of a flexible plate —26— which is secured at one end to the reservoir and its other end is attached to and adapted to be wound upon and unwound from a suitable roller —27— as best seen in Figs. 3 and 10, the adjacent end of the inner wall being returned upon itself to receive said roller. This roller is journaled at its opposite ends in the end heads —6— and is provided at one end with a suitable hand lever —28— for rotating the roller —27— and thereby moving the piston plate —26— radially. A packing —29— is interposed between one end of the roller —27— and adjacent head —6— to prevent leakage of the ink from the reservoir at this joint, the opposite journal bearing for the roller being closed. The piston or flexible plate —26— is substantially semi-cylindrical in cross section and extends from end to end of the reservoir leaving just sufficient clearance at the ends to permit the ink to be expelled from the inner side to the outer side of said piston and through the perforations in the stencil supporting segment where it comes in contact with and is distributed by the ink pad over the entire surface of the stencil.

The hand lever —28— for operating the roller —27— is provided with a pin —30— adapted to enter any one of a series of apertures —31— in the adjacent end head —6— to hold the roller —27— and piston —26— in its adjusted position, the lever —28— being made of spring metal to permit it to be sprung laterally to withdraw the pin —30— from the aperture with which it may be registered thereby permitting such adjustment and operating by its own spring tension to hold the locking pin in operative position.

The roller —27— is spring pressed endwise against the packing —29— by suitable

spring —32— which is interposed between one end of the roller —27— and inner face of the adjacent head —6— as best seen in Fig. 10, and one end of the piston plate —6— is inserted in a lengthwise slot in the roller —27—. It is evident that when it is desired to fill the reservoir with ink, the roller —27— may be operated to unwind the adjacent end of the piston plate —26— therefrom thereby forcing said piston plate radially and outwardly toward the perforated segment —7— thus leaving practically the full capacity of the reservoir for the reception of the ink after which the roller —27— may be rotated in the opposite direction to wind the adjacent end of the piston plate thereon thereby drawing the latter toward the inner wall of the reservoir and expelling the ink around the ends thereof into the outer portion of the reservoir and through the perforations of the segments —7— where it is readily taken up by the absorbent pad —8— and distributed evenly over the inner surface of the stencil.

The clamping bars or plates —11— and —11'— for the stencil —9— and ink pad —8— constitute an important feature of my invention in that they afford a convenient and adjustable means for receiving and clamping the ends of such parts and are readily inserted into or removed from the grooves —10— and when so inserted draw the ends of the stencil and pad inwardly around the ends of the segment and toward each other where they are firmly held in place by the tension of the stencil and pad.

The impression roller —2— which constitutes the other part of the printing couple is adjustable toward and from the lower side of the drum —1— or into and out of contact with the stencil and for this purpose is mounted in vertically movable bearings —35— which are guided in suitable ways —36— on the opposite ends of the main supporting frame as best seen in Fig. 15 and are normally spring-pressed toward the periphery of the drum by suitable springs —37—. The guides —36— are provided with laterally extending openings —38— to permit the presser roller —2— to be removed from the machine.

The means for moving the presser roller —2— away from the drum —1— and against the action of the springs —37— consists of suitable cams —39— which are connected by a shaft —40— and bear against suitable shoulders —41— on the ends of the main supporting frame —3—, said shaft being provided with an operating handle —42— by which the cams which are secured to the shaft may be rotated against the bearing shoulders —41—, the throw of the cams being sufficient to withdraw the compression roller —2— downwardly some distance from the side of the drum —1— and clear

from the path of movement of the stencil to prevent inking of the compression roller or mutilation of the stencil when the machine is not in use.

5 *Stop mechanism.*—This stop feed mechanism serves to regulate and synchronize the registering and feeding of the sheets one by one to the printing couple and consists as shown in Figs. 1 to 8 inclusive of a stop 10 roller —43— and suitable mechanism for controlling the action of said roller, said mechanism comprising a pawl —44— and a friction shoe —45— which latter is arranged to rotate with the printing drum —1—. The 15 roller —43— is substantially coextensive in length with that of the drum —1— or at least with that of the stencil which is carried by the segment —7— and is provided with a lengthwise groove —46— extending 20 from end to end and forming an abutment —47—against which the advance edges of the sheet are fed by hand to properly register such sheet preparatory to advancing it to the printing couple. This stop roller —43— is 25 operated intermittently one complete revolution during each revolution of the drum —1— and when at rest the open side of its groove —46— and its abutment —47— faces the support upon which the sheets to be 30 printed are stacked, that is the abutment extends in substantially a vertical position at the top of the roller or in a horizontal position substantially coincident with that upon which the edges of the sheets rest and 35 also in about the same horizontal plane as that of the meeting faces of the printing couple so that when the sheet is advanced it enters directly between the printing elements at the proper time and in position to 40 produce the printing upon the sheet where desired. The intermediate portion of the stop roller —43— which is adapted to engage with the stencil is preferably made of rubber but its ends are usually made of some 45 hard substance as metal or vulcanized fiber for forming bearings for the spring arms of a presser plate presently described.

The pawl —44— is centrally fulcrumed at —49— upon one end of the main supporting frame adjacent to the corresponding end of the roller —43— and is provided at its rear end with a stop shoulder —50— adapted to be engaged by a stop pin —51— on the adjacent end of the roller —43— to temporarily hold the latter against rotation by contact of the sheet with the abutment —47—. The opposite or front end of the pawl is provided with an idle roller —52— normally lying in the path of movement of 55 the shoe —45— which operates at the proper time to trip said pawl —44— to release the shoulder —50— from holding engagement with the stop pin —51—.

While the stop roll —43— is at rest the 60 uppermost sheet of paper is fed from the

stack by hand against the abutment —47— and in order that the roller —43— may be operated at the proper time to feed the registered sheet to the printing couple, it is necessary to provide some means for temporarily pressing the advance end of the sheet against the surface of said roller just in front of the abutment and into the groove —46— and for this purpose I have provided a bar —55— which is mounted upon a rocking shaft —56— and its rear edge is preferably rounded and spring-pressed by a suitable spring —57— toward the upper surface of the roller —43— but is held against the action of said spring a slight distance 75 away from the roller by rearwardly projecting fingers —58— on the ends of the bar —55—, said fingers being normally engaged with the outer edge or periphery of the abutment —47— when the roller —43— is 80 at rest as shown by dotted lines in Fig. 6.

In order that the presser bar —55— may be operated at the proper time to press the abutting or advance end of the sheet against the roller to permit the latter to feed such 90 sheet to the printing couple, I provide the rear end of the pawl —44— with a downwardly and rearwardly inclined shoulder —59— just below and in front of the stop shoulder —50— a sufficient distance to permit the entrance of the stop pin —51— between the upper end of said inclined shoulder and overlying portion of the pawl and against the stop shoulder —50—.

The shoe —45— is preferably concentric 100 with the axis of the drum —1— and is positioned relatively to the stencil so as to engage the roller —52— and thereby depress the front end of the pawl —44— some time before the printing portion of the stencil is aligned with the advance end of the sheet to be printed or at least some time before the advance end of the stencil reaches the point of contact with the impression roller —2— and during which operation the 105 shoulder —50— is elevated and released from holding engagement with the pin —51— and causes the inclined shoulder —59— to ride against the front face of said pin thereby effecting a slight degree of rotation of the stop roller —43— in the direction indicated by the arrow, Fig. 8 sufficient to move the outer edge of the abutment —47— out from under the presser bar —55— which allows said presser bar —55— to be 110 depressed against the advance end of the sheet and to temporarily hold the latter in contact with the periphery of the stop roller. Immediately following this latter action the friction shoe —45— comes in contact with 115 an annular friction face —60— on the adjacent end of the roller —43—, said shoe being of sufficient length to rotate the roller —43— one complete revolution and to allow the pawl —44— to gravitate into po- 120 125 130

sition to bring its shoulder —50— into the path of and to engage the pin —51— and thereby temporarily check the rotation of the roller —43— leaving the fingers —58— resting on the high point of the abutment to hold the presser plate —55— away from the roller thereby allowing the balance of the sheet to be fed rearwardly by the printing couple without friction between the presser 5 plate and stop roller. It is now clear that as each sheet is fed against the abutment —47— of the stop roller —43— while the latter is at rest and while the drum —1— is still rotating, the shoe —45— operates the 10 pawl —44— to trip it from holding engagement with the pin —51— and at the same time the inclined shoulder —59— operates against said pin to slightly advance the roller —43— sufficient to allow the presser 15 plate —55— to press the sheet against the periphery of the stop roller —43—. Immediately after this action of the presser plate —55— the shoe —45— contacts with and rotates the stop roller —43— one complete 20 revolution thereby feeding the sheet to the printing couple where it is caught and fed entirely through the machine with the imprint of the stencil thereon in the proper position.

30 It is sometimes preferable to provide means for beginning the printing at different distances from the advance end of the sheet and for this purpose the shoe —45— is adjustable circumferentially relatively to the stencil or drum and is mounted upon a radial arm —62— which is journaled at its inner end upon the hub of head —6— so as to move the shoe —45— concentrically around the axis of the drum. The radial 35 arm —62— is provided with a stop pin —63— adapted to enter any one of a series of apertures —64— in the adjacent end head of the drum —1—, said stop pin being in this instance, mounted upon one end of a 40 bell crank lever —65— which is fulcrumed at —66— and is provided at its other end with a pin —67— movable into and out of engagement with any one of a series of apertures —68— in the arm —62—. The 45 pin —63— passes through an elongated aperture —69— in the arm —62— to allow a limited adjustment of the lever —65— for effecting a closer adjustment of the shoe —45— relatively to the drum. That is, by 50 withdrawing the pin —63— from locking engagement in the apertures —64—, the shoe —45— may be rotated by hand to approximately the desired position of adjustment, whereupon the pin —63— may be 55 caused to reenter the nearest aperture —64—, it being understood that during this adjustment the pin —67— is in interlocking engagement with one of the apertures —68—. Now, if the adjustment is not 60 quite correct, the pin —67— may be with-

drawn from its aperture —68— by springing the arm —65— outwardly, thereby permitting said arm or lever —65— to be rocked upon its pivot —66— with the pin —63— still locked in one of the apertures —64—, the elongated slot —69— permitting the relative movement of the parts —6— and —62— while the opening through which the pivot —66— is passed is also elongated to compensate for the varying distances between the centers of the pivots —63— and —66— during such adjustment. After this extra adjustment has been made, the pin —67— is allowed to again enter one of the apertures —68— to lock the members —6— and —62— against further relative movement. The arm —62— is made of spring metal tensioned toward the adjacent end of the drum but adapted to be sprung outwardly to disengage the pin from the aperture with which it may be registered, thus permitting the circumferential adjustment of the shoe. In like manner the handle end of the lever —65— is made of spring metal normally tensioned toward the arm —62— to hold the pin —67— in operative position but is adapted to be sprung outwardly to disengage such pin —67— from the aperture with which it may be registered thus permitting a further adjustment of the drum relatively to the lever. 95

Sheet supporting and retarding means.— The sheets as —a— to be printed are stacked in suitable quantities one upon the other upon an inclined table or support —70— having a roughened retarding face —71— at its front end, said retarding face being disposed at an obtuse angle with the remaining portion of the table and in substantially the same horizontal plane as the upper face of the stop roller —43—. The sheets are, therefore, supported in an inclined plane and gravitate endwise against the roughened surface —71— which is made of sand paper, emery or other rough material and serves to hold the underlying sheets against rearward feeding while the upper sheet is being fed by hand across said roughened surface and against the abutment of the stop roller —43—. This table is 100 loosely held between suitable rests or shoulders —74— and —75— which project inwardly from opposite sides of the frame —3— and are located at different distances from the longitudinal center of the machine, 105 the supporting pin —74— being preferably located in close proximity to the roller —43— and engage the upper surface of the adjacent ends of the table while the other shoulders —75— are located farther forward and engage the under side of the adjacent ends of the table, the latter shoulders being adapted to be inserted in one of a series of apertures —76— to permit the 110 table to be adjusted to different angles and 115

at the same time permitting such table to be withdrawn by simply elevating its front end and drawing it forwardly and upwardly.

- 5 In Fig. 16 I have shown a drum —1— as provided with a modified actuating mechanism for the stop roller consisting of a ring —80— adjustable circumferentially around and upon one end of the drum and provided 10 with a toothed rack —81— adapted to engage a mutilated gear —82—, on one end of a stop roller —83—. The rack —81— and mutilated gear —82— constitute a positive driving mechanism for the stop roller —83— 15 to take the place of the friction shoe —45— and friction wheel —60— of the device shown in Figs. 1 to 8 inclusive, the toothed rack —81— having substantially the same number of teeth as the gear —82— so as to 20 rotate the stop roller —83— one revolution during each revolution of the drum. The ring —80— is adjustable circumferentially around and upon the drum for the same purpose that the shoe —45— is adjustable and is 25 held in its adjusted position by a clamping screw —86— as best seen in Figs. 16 and 18 and additional screws —87— which are located at intervals in the end of the drum to retain the ring —80— in place against 30 endwise displacement. The greater portion of the periphery of the ring —80— is smooth and concentric with the axis of the drum and in the same plane as the pitch line of the rack and rides against a concave face 35 —88— on the mutilated gear —82— to hold the stop roller —83— against rotation until about ready to be engaged by the rack —81—. In Fig. 17 I have shown a presser plate —89— similar to the presser plate 40 —55— except that the rear edges of the fingers —58— normally bear against inclined or beveled shoulders —90— on the ends of the roller —83— but serve the same purpose namely to hold the presser bar away from 45 the roller when the latter is at rest to permit the sheets to be fed one by one against the abutment —49—. A short portion of the periphery of the ring —80— is cut away at —93— slightly within the pitch line just 50 in advance of the rack —81— so as to clear the bearing face —88— of the gear —82— and thereby permit the spring fingers —89— of the presser bar to ride downwardly against the inclined face —90— and thereby 55 rotate the roller —83— a slight degree sufficient to allow the presser bar —89— to ride against the sheet of paper which may abut against the abutment —49—. Otherwise the action of this device shown in Figs. 16 60 to 19 inclusive is substantially the same as that described in the construction shown in Figs. 1 to 8 inclusive.

Referring again to the ink reservoir it will be seen that by making the plates 65 —23— and —26— substantially coextensive

in area with that of the perforated stencil plate and stencil —9—, they constitute a covering which reduces the evaporation of the ink, and thereby prolongs the efficiency of the machine without reinking.

Another important feature of this invention is the means for stripping the paper from the stencil as it is fed through the machine. This is particularly effective in operating upon extremely thin paper to prevent the latter from adhering to and being carried around with the stencil during the printing operation. This stripping means comprises, in this instance, two presser fingers —94— extending transversely to the axis and in close proximity of the presser roller —2— and also at opposite ends of the perforated or printing portion of the stencil, the rear ends of said fingers, which preferably consist of springs being spring pressed downwardly slightly below the upper plane of said roller —2—, so as to deflect the longitudinal edges of the sheet downwardly at the ends of said roller thereby stiffening the advancing sheet and cause it to travel in a horizontal plane rearwardly away from the stencil. The front ends of the fingers —94— are disposed in a plane slightly above the plane of travel of the sheet as it is fed forwardly by the stop roller, so as to cause the edges of said sheet to ride under said fingers. The bearing points of the fingers, which engage the sheet, lie directly over the axis of the roller —2—, so as to turn the edges of the sheet downwardly directly at the meeting faces of the roller —2— and stencil where the pressure upon the printed sheet is greatest to prevent sticking of the sheet to the stencil while traveling through the machine.

It is desirable in this class of machines to prevent backward movement of the drum carrying the stencil, and for this purpose I have provided a brake shoe —96— pivoted at one end at —97— to a stationary support —98—, and having its free end riding against an annular flange or bearing —100— on one end of the drum, the distance between the brake faces of the movable member —96— and axis of the drum through the pivot —99— being greater than the radius of the inner bearing faces of the flange —100— which permits the drum to be rotated in the direction indicated by the arrow "X", and prevents its rotation in the opposite direction.

The operation of my invention will be readily understood upon reference to the foregoing description and the accompanying drawings. Attention, however, is called to applicant's co-pending applications #537,440, filed Jan. 11, 1910, and #604,604 filed Jan. 25, 1911. The relation between each of said co-pending applications and the present case is that each machine shows a stencil sup-

- porting drum, means for regulating the head space on the printed sheet, and a movable abutment against which the sheets are fed to aline and direct the sheet between the stencil drum and underlying presser roll.
5. What I claim is:
1. In combination with a rotary stencil supporting drum and actuating means therefor, a presser roller coacting with the drum, a sheet support some distance in front of the presser roller, rotary alining and feeding means between the presser roller and paper support, and means rotating with the drum for actuating the feeding means intermittently one revolution at a time.
  15. 2. In combination with a rotary stencil supporting drum, a presser roller coacting with the drum, a sheet support in front of the presser roller, a stop roller located between the sheet support and presser roller and provided with a lengthwise abutment for the advance ends of the sheets, and means rotating with the drum for actuating said stop roller.
  25. 3. In combination with a rotary stencil supporting drum, a presser roller coacting with the drum, a support for the sheets to be printed, rotary means between said sheet support and presser roller for alining and feeding the sheets between the presser roller and drum, means rotating with the drum for actuating said feeding and alining means, and separate means controlled by the drum for stopping the alining and feeding means at the end of each revolution.
  35. 4. In a stencil printing machine, a stop roller having a lengthwise abutment for the advance edge of a sheet to be printed, and a sheet support having a retarding rest for the edges of the sheets in the plane of said abutment.
  45. 5. In a stencil printing machine, a stop roller having a lengthwise abutment for the advance edge of a sheet to be printed, and an inclined sheet support having a substantially horizontal retarding rest for the edges of the sheet, said rest being disposed in substantially the same horizontal plane as the abutment.
  55. 6. In a stencil printing machine, a stop roller having a lengthwise abutment for the advance edge of a sheet to be printed, and an inclined sheet support having a substantially horizontal roughened retarding rest for the advance edges of the sheets, said rest being disposed in substantially the same plane as and in close proximity to the abutment.
  65. 7. In a stencil printing machine, a stop roller having a lengthwise abutment for the advance edge of a sheet to be printed, and a presser-bar normally spring-pressed against the periphery of the abutment and adapted to press a sheet against the roller as the latter is rotated.
  8. In a stencil printing machine, a stop roller having a lengthwise abutment for the advance edge of a sheet to be printed, and a presser-bar normally spring-pressed against the periphery of the abutment and adapted to press a sheet against the roller as the latter is rotated, and means for actuating the roller sufficient to move the abutment from engagement with the presser bar.
  15. 9. In a stencil printing machine, a stop roller having a lengthwise abutment for the advance edge of a sheet to be printed, a rotary stencil supporting drum, and means synchronized therewith for rotating the stop roller one revolution at each revolution of the drum.
  25. 10. In combination with a rotary stencil supporting drum, a presser roller coacting therewith, a support for the sheets to be printed, a feed roller between the presser roller and said support and provided with a lengthwise abutment for the ends of the sheets, and means rotating with the drum for actuating the feed roller one revolution during each revolution of the drum.
  35. 11. In a stencil printing machine, a rotary stencil support, a roller having a lengthwise recess in its periphery forming an abutment for the advance end of the sheet, and means controlled by the stencil support for actuating the roller.
  45. 12. In a stencil printing machine, a rotary stencil support, a roller having a lengthwise recess in its periphery forming an abutment for the advance end of the sheet, a presser-bar spring pressed toward the roller to press the sheet against such roller, and means controlled by the stencil support for controlling the action of said presser bar.
  55. 13. In a stencil printing machine, a rotary stencil supporting drum, a presser roller coacting therewith, a support for the sheets to be printed, a rotary alining abutment for the sheets between said sheet support and presser roller, means rotating with the drum for shifting said abutment once during each revolution of said drum, and additional means moving with the abutment for feeding the sheets one by one from the support to and between the presser roller and drum.
  65. 14. In a stencil printing machine, a rotary stencil support, a roller having an abutment for the advance end of a sheet to be printed, a presser bar spring pressed toward the roller, means normally holding said bar away from the roller, and means comprising an actuator on the stencil support for moving said holding means from its holding position.
  75. 15. In a stencil printing machine, a rotary stencil support, an impression roller adjustable toward and from the support, a rotary abutment in front of the meeting faces

of the support, and roller, a presser bar normally spring-pressed against the abutment, and means comprising an actuating member rotatable with and adjustable relatively to said support for controlling the action of the presser bar and abutment.

In witness whereof I have hereunto set my hand this 26th day of December 1908.

EDWIN A. COX.
